Attorney

UNITED STATES PATENT OFFICE.

ROY B. FARRAR, OF SPOKANE, WASHINGTON.

ASH PAN.

Application filed February 16, 1926. Serial No. 88,545.

My present invention relates to improvements in ash pans designed for use in the ash pits of stoves and furnaces. The primary object of the invention is the provision of an ash pan that is of a size as to completely occupy the floor of the ash pit of a stove or furnace in order that all of the ashes falling from the fire pot may be caught in the receptacle, and at the same time so constructed as to enable it to be withdrawn with facility from the ash pit through its comparatively small door opening. To this end the ash pan comprises a plurality of sections arranged in such relation and equipped with handles so that they may be manipulated with convenience and placed in or withdrawn from the ash pit with facility. In the exemplification of the invention herein described and illustrated the ash pan comprises a central or main section that may be handled as a unit and a complementary pair of smaller side sections that may be manipulated as a unit.

The invention consists in certain novel combinations and arrangements of parts for carrying out the above indicated results as will hereinafter be more fully set forth and claimed.

In the accompanying drawings I have illustrated one complete example of the physical embodiment of my invention wherein the parts are combined and arranged in accord with the best mode I have thus far devised for the practical application of the principles of my invention.

Figure 1 is a perspective view of the ash pan involving my invention with the sections in assembled position as used in an ash pit.

Figure 2 is a transverse, vertical sectional view of the ash pan on line 2—2 of Figure 1.

Figure 3 is a perspective view of the two side sections assembled for handling as a unit.

Figure 4 is an enlarged, detail sectional view of adjoining inner walls of the side sections, showing by dotted lines the handles thereon in position for use.

In the preferred form of the invention I utilize three sections, as a main section 1 and two smaller side sections as 2 and 3. The main or intermediate section is preferably rectangular in shape and provided with front handle 4 and rear handle 4' to facilitate handling of it when emptying the

ashes therefrom. The side sections also have front handles as 5 and 5' of the usual pivoted or hinged type similar to handles 4 and 4' of the main section.

The pan sections are preferably provided each with a transversely disposed cross bar as 6 connecting its side walls and located near the top of the section. These bars not only perform the functions of braces for strengthening the pan sections, but may also be used as handles for the respective sections when the latter are empty.

When used in circular ash pits the outer side walls of the side sections and the back wall of the main section are rounded to conform to the walls of the ash pit, but the inner side walls of the side sections as 7 and 7' are arranged on straight lines in parallelism and parallel with the side walls of the main section.

As best seen in Figure 2 the inner walls 7 and 7' of the two side sections are higher than the other walls of said sections, and the side walls of the main section are higher than these inner walls of the side sections. Along the upper edges of the side walls of the main section are fashioned angular flanges 8 and 8' which overhang the respective walls 7 and 7' of the side sections. Thus when the two side sections are placed within the ash pit and separated or spaced apart, the main section is slid into place between these sections and the flanges 8, 8' overhang the walls 7 and 7' to prevent ashes falling between the sections and to draw the two side sections toward and hold them in close relation to the main section.

For the purpose of emptying the pan of ashes the main or intermediate section is first removed, and then the two side sections are brought together, as in Figure 3, and removed as a unit.

In order that the two side sections may be handled as a unit, each of them is provided on the inner face of its inner or straight wall, as 7, 7', with handles 9 and 10. These handles are in the form of inverted U-shape yokes, disposed vertically at the sides of the sections and vertically slideable in double looped brackets 11 secured to the walls of the sections. At their lower ends the handles are fashioned with out turned lugs 12 which prevent displacement of the handles and receive the load when used as carriers in dotted position in Figure 4. The two handles 9 and 10 are located in such

position with relation to one another that they may readily be grasped in one hand when lifted above the top edges of the walls 5 and 5' and when the sections are assembled as in Figure 3 the two handles 5 and 5' may be grasped in the other hand for the purpose of carrying these two sections as a unit when emptying them of ashes.

When the pan is in place in the ash pit 10 the adjustable or slidale handles 9 and 10 are dropped to their lower positions as shown in full lines Figure 4 and in the other figures of the drawing.

Having thus fully described my invention 15 what I claim as new and desire to secure by Letters Patent is—

1. An ash pan comprising a pair of side sections having flat vertical inner walls of an elevation greater than the outer walls

thereof, an intermediate section having flat 20 vertical side walls of an elevation greater than the side inner walls of said side sections, and downturned flanges on the tops of the side walls of said intermediate section, said flanges extending at an incline 25 down over the edges of the inner walls of said side sections in service position.

2. In a sectional ash pan having a pair of sections adapted to be arranged in abutting side to side position for transportation, vertically slidale handle members carried by the meeting side walls of said sections, said handles being arranged for elevation in juxtaposition above the tops of said sections in transporting position, and for depression 35 beneath the tops in service position.

In testimony whereof I affix my signature.
ROY B. FARRAR.
